UNITED STATES PATENT OFFICE.

JOSEPH H. BRANSON AND BENJAMIN BRANSON, OF FLUSHING, OHIO.

PUMP.

SPECIFICATION forming part of Letters Patent No. 249,885, dated November 22, 1881.

Application filed July 2, 1881. (Model.)

To all whom it may concern:

Be it known that we, JOSEPH H. BRANSON and BENJAMIN BRANSON, both citizens of the United States, residing at Flushing, in the 5 county of Belmont and State of Ohio, have invented certain new and useful Improvements in Pumps; and we do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 This invention relates to certain improvements in pumps; and it consists in certain details of construction, which will be hereinafter more fully described, and then pointed out in the claims.

20 In the accompanying drawings, Figure 1 shows a side elevation; Fig. 2, an enlarged sectional view of the pump-cylinder and connections. Fig. 3 is also an enlarged view, partly in section, showing the manner of connecting the parts; and Fig. 4, a detail plan view of the fastening-lugs.

25 A represents the pump-cylinder, which is held between the coupling B, into which the discharge-pipe C is screwed, and the coupling 30 D, which receives the suspending-rod, which may be solid, or it may be hollow to form a vacuum-chamber, E, which rod or pipe also passes loosely through a socket, b, formed in the coupling B, and is connected above to the base-plate; or it may form part of the standard.

35 Between the upper coupling, B, and the cylinder A is a packing-ring, a, and between the lower coupling and the cylinder is a packing formed of the leather or other suitable material of which the valve V is made. This valve 40 differs from the style of valve usually employed in this style of pump, inasmuch as it is provided with a beveled disk, e, fitting on a beveled seat, d, in the coupling D. This disk may be 45 either made separately and attached by the bolt that holds the weight on the packing-leather, or this packing-valve may be made of a single piece of rubber, leather, or other suitable material molded into shape.

50 The rod or pipe E screws into the coupling D, passes loosely through the socket b of the

coupling B, and extends upward through the platform or base-plate F, to which it is securely fastened by a set-screw, f, or other suitable fastening, thereby forming a support for the 55 coupling D, and the inlet-pipe screwing into the bottom of said coupling. The upper end of the pipe or rod E also extends through the handle-supporting casting or head-plate G, and is supplied with a cap-nut, g, as represented in 60 Fig. 1.

The discharge-tube C screws into the coupling B and extends upward, and is fastened to the base-plate F in the same manner as the rod or pipe E, its upper end, however, after 65 passing through the head-plate G, being provided with a thread to screw into the union h, which is provided with an internal right thread to receive said discharge-tube, and with an external left thread to screw into the lower end 70 of the curved spout H. Short sections of pipes or rods I are screwed, one at each side, into the base-plate F, and have their upper ends fitted into sockets in the head-plate G, their upper 75 ends being screw-threaded and provided with nuts i. By this construction the pipes C E form two posts and the short sections I two additional posts at different points for supporting the head-plate G.

The parts are secured tightly together by 80 turning the nuts i of the sections I, so as to force the head-plate G upward against the union h and the cap-nut g. The two couplings B D are securely drawn together and against the ends of the cylinder A by bolts K, which 85 pass loosely through holes in the lugs k k of the lower coupling and lugs l l of the upper coupling, and are provided with nuts m m at their upper ends. The lugs l l are each provided with a side opening, l', as shown in Fig. 4, 90 and are also made with conical recesses to receive the conical faces of the fastening-nuts, so that by loosening the nuts the bolts can swing outward through the opening l' without entirely removing the nuts.

95 If preferred, the heads may be made conical instead of the nuts. Instead, however, of making the nuts or heads with conical faces, as described, circular recesses may be made in the lugs l large enough to receive the entire lower 100 surface of an ordinary nut.

When the fastening-bolts have been detached

from the coupling B, as described, the coupling B can be raised vertically with its packing-cylinder L, to allow access to the interior of the pump for inspection or repairs, by loosening 5 the set-screw f' , and drawing the discharge-pipe C upward, the socket or sleeve b of the coupling B sliding vertically on the suspending rod or pipe E during this operation, so as to act as a guide for insuring the vertical movement of 10 the coupling. When the upper coupling is raised to the desired length it can be held in position by tightening the set-screw f' . The set-screws $f'f'$, when screwed into place after the bolts k have been tightened, relieve these bolts 15 of all strain. By these means the cylinder, piston, valve, and packing-rings can each be removed for inspection or renewal without raising the whole pump above the platform, leaving the inlet-pipe, the lower coupling, and the 20 suspending pipe or rod in their normal position in the well.

By making the valve and seat of the shape shown and described a tighter fit is obtained, and the beveled seat prevents the lodgment of 25 any foreign material.

What we claim as new is—

1. In a pump having its cylinder suspended below the base-plate, a suction-pipe suspended independently of said cylinder and the discharge-pipe coupling, whereby the cylinder may be removed without disturbing the suction-pipe, substantially as described. 30

2. In a pump having its cylinder suspended below the base-plate, a suction-pipe suspended 35 below said base-plate by a rod connected directly to the base-plate, and connected to the suction-pipe by a suitable coupling, whereby the suction-pipe is properly supported when the cylinder is removed, substantially as specified.

3. A pump having its suction-pipe united 40 by a coupling directly with a branch pipe extending above the cylinder to form a combined vacuum-chamber and suspending-rod, and opening directly into the coupling, substantially as specified.

4. In a pump, the combination of the coupling D, carrying the suction-tube, with the suspending-rod E, whereby the suction-tube may

be held in its normal position when the cylinder is removed, substantially as described. 50

5. In a pump, the coupling B, provided with an opening for the discharge-tube C, and the coupling D, having an opening for the suspending-rod E, in combination with said tube C, rod E, the cylinder A, and suitable fastening devices, substantially as described. 55

6. In a pump, the couplings B D, one of which has slots provided with recesses, in combination with the cylinder A, and bolts having heads or nuts fitting into the recesses in the 60 coupling, substantially as and for the purpose set forth.

7. In a pump, the couplings B D, in combination with the cylinder A, the discharge-tube C, rod E, and bolts K, substantially as described. 65

8. In a pump, the couplings B D, having slots provided with recesses, in combination with the cylinder A, discharge-tube C, rod E, and bolts having nuts or heads fitting into recesses, substantially as described. 70

9. In a pump, the combination of the base-plate F, provided with set-screws $f'f'$, with the couplings B D, discharge-pipe C, and the suspending pipe or rod E, substantially as described. 75

10. In a pump, the combination of the base-plate F, provided with set-screws $f'f'$, with the head-plate G, union h , cap-nut g , sections I, and nuts i on said sections I, substantially as described. 80

11. In a pump, the coupling B, provided with an opening for receiving the upper cylinder, a lower opening concentric with the upper one for receiving the lower cylinder, an extension for receiving the discharge-pipe, and a guiding- 85 socket, b , substantially as described.

In testimony whereof we affix our signatures in presence of two witnesses.
